UNITED STATES PATENT OFFICE

JOHN H. BARR, OF ITHACA, NEW YORK, ASSIGNOR TO BARR-MORSE CORPORATION, OF ITHACA, NEW YORK, A CORPORATION OF NEW YORK

TYPEWRITER

Application filed June 29, 1928. Serial No. 119,422.

This invention relates to typewriters and the like, and more particularly to the mechanism for feeding the paper therethrough in contact with the platen for printing purposes.

An object of the invention is to generally improve and simplify the mechanism of such devices for guiding the sheet or paper to be printed upon to and around the platen, and for holding it against the platen so as to be propelled with the platen in presenting the correct portions successively for printing purposes; which will provide a more dependable and positive feeding action between the sheet or element to be printed upon and the platen; and with which the pressure between the feeding and guiding mechanism for the sheet or paper and the platen will be distributed so as to cause an even feeding of the paper throughout the length of the platen.

A further object is to provide improved and simple means for holding the paper or sheet and conducting it through printing position, and which may be placed in either effective or ineffective position for holding the paper to the platen, in a simple and practical manner.

A further object of the invention is to provide improved mechanism for guiding sheets or paper to and around the platen for printing purposes, which will hold the paper or sheets firmly and uniformly against the platen during feeding and printing operations, and which may be manipulated to release the pressure between the paper or sheets upon the platen in order to adjust the paper or sheets upon the platen.

A further object of the invention is to provide mechanism for accomplishing each and all of the above objects which will be capable of manufacture, to a maximum extent, from stamped sheet metal, and which will be exceptionally simple, durable, convenient, and relatively inexpensive.

Various other objects and advantages will be apparent from the following description of one embodiment of the invention, and the various novel features will be particularly referred to and pointed out in connection with the appended claims.

In the accompanying drawing:

Fig. 1 is a side elevation of the paper feeding mechanism of a typewriter constructed in accordance with this invention;

Fig. 2 is an end elevation of the same;

Fig. 3 is a transverse, sectional elevation of the same, with the section taken approximately along the line 3—3 of Fig. 1, and with certain of the parts broken away to illustrate details of construction;

Fig. 4 is a perspective of one of the cams of the same;

Fig. 5 is another sectional elevation of the same, with the section taken approximately along the lines 5—5 of Fig. 1;

Fig. 6 is an end elevation of a portion of the same, with the parts in different relative positions from those shown in Fig. 2;

Fig. 7 is a plan of a portion of the mechanism of the same;

Fig. 8 is a sectional elevation of a portion of the paper feed shell, with the section appearing as along the lines 8—8 of Fig. 1; and

Fig. 9 is an elevation partly in section of certain details.

Fig. 10 is a sectional elevation through one of the paper bail rollers; and

Fig. 11 is an end elevation of the same.

In the illustrated embodiment of the invention, a platen 10 of any suitable construction is rotatably mounted in plates 11 which project from a suitable carriage base 12 that is mounted for travel across the typewriting machine in any suitable or desired manner, as well understood in the art. Such a mounting of the carriage is illustrated in Fig. 2 in which the carriage base is supported upon and guided along a track 13 by suitable ball or roller bearings 14 interposed between the track and opposed channel grooves 15 of the carriage base. The plates 11 may be provided with slots 16 extending from their upper edges to the bearings 17 of the plates, so that the platen may be mounted in the plates 11 by lowering its spindle through the slots 16 into the bearings 17. Suitable means for aligning and adjusting the spindle through the bearings may be employed, but such de-

tails have been omitted here, since they are not a part of the present invention.

The spindle may be confined in the bearings 17 of the slots 16 in any suitable manner, such as by latch levers 18 which are pivoted at 19 to the plates 11, and provided with hook portions which engage over the platen spindle and confine it within the bearings 17 of the slots 16. A spring 20 may be connected between each latch lever 18 and a suitable pin on the adjacent plate 11, so as to normally urge the latch lever in a direction to lock the platen spindle within the bearings 17 of the plates 11. The extreme end of each latch lever may be curved arcuately, as at 21, so that when the platen spindle is forced into the slots 16, the latch levers will be automatically cammed aside to permit entrance of the platen spindle into the bearings 17 of the slots 16, whereupon the springs 20 will snap the latch levers automatically into latching engagement with the platen spindle.

A pair of lever arms 22 are pivotally mounted intermediate of their ends by pins 23 upon the plates 11, and corresponding ends of the levers 22 are connected by a rod 24 which forms, with the two levers, a paper holding bail which may be rocked in directions to carry this cross arm portion formed by the rod 24 to and from the platen 10. The rod 24 which forms the cross arm portion of the bail may have rotatably and slidably mounted thereon suitable rubber rollers 25, for holding against the platen the sections of sheets of paper which have been carried with the platen through printing position. The rod 24 may also have a flat surface portion 26 carrying suitable scale graduations. This flat portion may be formed by milling off a face upon a cylindrical wire or rod.

Referring particularly to Figs. 1, 10 and 11, each roller 25 has a sleeve 25^a of a size to fit the rod 24 and slide and rotate thereon. Upon one end of this sleeve a rubber roller 25^b is fitted and secured thereto such as by cement. The sleeve 25^a, at one end, is provided with an internal annular groove or recess 25^c which rotatably receives a slit bushing or friction element 25^d. This bushing or element 25^d may be formed by providing a cylinder with a single slit 25^e (see Fig. 11) along its length, so as to be sprung open slightly when fitted upon the rod 24. The split bushing or friction element may be confined within the recess or groove 25^c after insertion therein by spinning over and inwardly the adjacent free end of the sleeve 25^a so as to form an inwardly extending annular retaining flange 25^f. The split sleeve 25^d frictionally grips the rod 24 at all times, and thus frictionally holds the composite roller 25 in all of its adjusted positions along the rod without limiting free rotation of the

sleeve 25^a and rubber roller 25^b upon the rod.

A link 28 is pivotally connected by a pin 29 to each lever 22, and the free end of each link is provided with a slot 30 extending for a considerable distance from its free end. The slot 30 of each link slidably straddles a pin 31 projecting from a face of the plate 11, the pin 31 preferably having an annular groove 32 (see Figs. 1 and 6) in which the link is slidably and rockably disposed, and held against movement endwise of the pin on which it is mounted. A helical compression spring 33 is provided upon each arm of the free end of each link 28 along the slot 30, and is compressed between the wall of the link at the inner end of the slot and a plate 34 which is provided with apertures through which the arms formed by the slot 30 slidably extend. The plate 34 bears against the pin 31, so that the springs 33 will yieldingly urge each link 28 in a direction to withdraw it from the pin 31 upon which it is both slidably and rockably mounted.

When the cross rod 24 of the bail is somewhat spaced from the platen, such as in the position it would occupy when the bail is swung away from the platen, the pivot 23 of a lever 22, the pivot pin 29, and the pin 31 at each end of the platen may be in dead center alignment with one another, and, therefore, the bail, upon being somewhat displaced in either direction, will be yieldingly urged in the corresponding direction, from that dead center position, in one of which directions it will be urged toward the platen so as to yieldingly press the rollers 25 against the platen. When the bail is swung away from the platen beyond the dead center position, it will then be yieldingly urged in a direction further from the platen.

Each link 28 is provided with an ear 35 (see Fig. 6) for engagement by a tail portion 36 of the lever 22, to which it is connected, shortly after the bail is shifted in a direction away from the platen beyond the dead center position, so that the bail will yieldingly be held in a retracted position away from the platen. When the bail is shifted towards the platen, it will, after passing the dead center position, be shifted yieldingly against the platen so as to confine against the latter any paper or sheet material which has been moved with the platen beyond printing position. The rod 24 may be confined between the levers 22 by screws 37 which pass through the levers 22 and are threaded into the ends of the rod 24. From this, it will be observed that the paper holding bail may easily be almost entirely formed of stamped sheet metal parts and stock rods.

A bearing rod 38 extends between the plates 11, and one end is reduced in size and rotatably received in an aperture 39 in one of the plates, with the shoulder at the reduced portion fitting against the inner face of the plate 130

11 in which it is rotatably mounted. The other end of the rod 38 is provided with an axial recess 40 and terminates in proximity to the other plate 11. A screw 41 is threaded through an aperture in the last mentioned 5 plate 11 and provided with a shank 42 of reduced diameter which is rotatably received within the recess 40 of the rod 38.

A plurality of arms 43 are rotatably mounted upon the rod 38, part of the arms extending 10 in one direction peripherally of the platen and the others extending peripherally in the other direction around the platen. The arms upon each side of the platen are grouped 15 in pairs, and each pair supports a roller spindle rod 44 which extends between the arms of that pair. Upon each spindle rod 44 a pair of the usual paper feed rollers 45 are rotatably mounted and spaced apart by a suitable 20 bushing 46 which is also rotatably mounted upon the spindle rod 44. The arms 43 of each pair, together with the connecting spindle rod 44, constitute a bail which is oscillatable upon the rod 38 so as to carry its feed 25 rollers 45 into and out of contact with the platen surface.

The extreme tip end of each spindle rod 44 is threaded for a short distance, as shown in Fig. 9, and the arms 43 are threaded somewhat loosely upon such threaded ends so that the spindle rod cannot become detached from its arms. In assembling, the arms 43 are screwed on the two ends of the rods 44, and are then lined up and slipped upon the rod 38, which restrains arms 43 against becoming 30 unscrewed. However, the spindle rod 44 can tilt or move slightly within the arms 43 in an angular direction, so that the rollers 45 may engage uniformly with the platen surface 35 along the entire length of the bail upon which they are supported. Any tendency of a spindle rod 44 to rotate and thus become detached or unthreaded from the arms 43 is prevented, either by engagement of the unthreaded ends 40 of the rods with the arms 43, or as illustrated by providing shoulders upon the end portions of the spindle rods for engagement with the arms 43. Thus, rotation of a spindle rod in either direction will be checked by engagement 45 at the ends of the thread or a shoulder thereof with one of the arms 43, and, therefore, the spindle rods cannot rotate sufficiently 50 to become unthreaded from an arm 43. Each bail carrying the rollers 45 is disposed 55 opposite a similar bail carrying rollers 45, so that the rollers of these two bails contact with the platen surface at points spaced apart peripherally of the platen.

A yoke 47 is secured to the platen support 60 12 in any suitable manner, such as by screws 47^a (Figs. 2, 3 and 5) between each pair of arms 43 that extend along one particular side of the platen and this rod 38 extends through the side arms of the yokes. A pressure arm 65 18 is provided with angularly extending and

parallel ears 49 which are pivotally mounted upon a pin 50 that extends between the arms of each yoke 47, the pin 50 being confined against endwise movement in the yoke by suitable locking pins 51 that extend transversely through the pin 50 and along the faces of the yoke. A somewhat similar pressure arm 52 is similarly pivoted upon the pin 50 between the ears 49. The two pressure arms 48 and 52 extend from the yoke on opposite sides of the rod 38, thence along opposite sides of the platen, and bear upon the bushings 46 provided upon the bail spindle rods 44 between the feed rollers 45.

A bolt 53 extends through an aperture in one of the arms 48, with its head fitting against that arm, and passes through a similar aperture in the other arm 52, the two pressure arms 48 and 52 having intermediate their ends for this purpose angularly offset approximately parallel portions. The free end of the bolt 53 carries an adjustable abutment member 54, such as a nut which is threaded thereon, and a compression spring 55 is confined between the arm 52 and the abutment member 54, so as to urge the pressure arms 48 and 52 yieldingly toward one another and toward the platen, and press the rollers 45 yieldingly into contact with the platen. By adjusting the abutment members or nuts 54, 95 the pressure of the rollers 45 upon the platen may be varied.

The pressure arms 48 and 52 are placed approximately midway of the length of each pair of bails with which they cooperate, and with the provision for a limited tilting of the bail spindle rods 54, the pressure of the rollers 45 will be substantially uniform along the entire length of each bail and, therefore, the feeding effect upon sheet material disposed between the rollers and the platen will be uniform throughout the length of each bail. By adjustment of the nuts 54, the pressure may be made uniform throughout the entire length of the platen. I have found that four sets of bails on the rod 38 with the two sets of pressure arms 48 and 52 provide a very satisfactory feeding action when cooperating with the platen. With longer platens to enable the use of very wide paper, additional sets of rolls and pressure arms of the same construction can be provided.

A cam element 56 is secured, in any suitable manner, such as by a pin 57, to the rod 38 between each pair of pressure arms 48 and 52 for oscillation with the rod 38. Such a cam is shown separately in Fig. 4 and is provided with two angularly spaced cam noses 58 which are normally in the positions shown in Fig. 3, so that when the rod 38 is rocked in one direction both noses of each cam will engage with the pressure arms 48 and 52 with which they cooperate and cam the arms apart, as shown in Fig. 5, against the action 125 of the springs 55. A handle arm 59 is secured 130

to one end portion of the rod 38, such as by a pin 60 which passes transversely through a boss of the arm and the rod 38, so that whenever the arm 59 is rocked it will cause a rocking of the rod 38, and a separation or 5 release of the pressure arms 48 and 52 through the action of the cams 56.

A spacing bushing 61 is provided upon the rod 38 between one plate 11 and one set 10 of arms 43 which are nearest thereto, as shown in Fig. 1, and another spacer bushing 62 is disposed on the rod 38 between the arm 59 and the other pair of arms 43 which are nearest the other end of the rod 38. Still other spacer bushings 63 are disposed between the arms of the yokes 47 and the arms 43 of the bails with which the yokes cooperate, and prevent lateral displacement of the arms 43. A spacer bushing 64 may also be provided upon the rod 38 between the abutting 20 pairs of bail arms 43 so as to space each pair of bails from the other abutting pair. Thus, all of the arms 43 and the yokes will be properly spaced apart with respect to one another along the rod 38.

A concave paper deflector 65, representing a segment of a cylindrical shell, is disposed beneath the platen and is substantially co-extensive in length therewith. The deflector 30 at its ends is provided with downwardly extending flanges 66 which carry slots 67 extending inwardly from their free ends and straddling the spacer bushings 61 and 63, so as to confine the deflector beneath the platen while permitting limited vertical movement 35 thereof. A tongue 68 is struck downwardly from the deflector 65 at a point intermediate of its ends, so as to depend between the arms 43 of abutting bails and hold the deflector 40 against movement endwise of the platen. The deflector is supported upon the corners of the arms 52 formed where the offset portions join the free end portions which bear against the spacer bushings 46 on the bail spindle 45 rods 44, as shown in Figs. 3 and 5. The forward portion of the deflector is supported, or limited in its motion, by contact against the spacer bushings 46 upon the bail spindle rods 44.

The deflector 65 is provided with apertures 50 69 that are aligned with the rollers 45 and through which the rollers 45 may project and contact with the surface of the platen. Thus when the rollers 45 are in contact with the platen, as shown in Fig. 3, for example, the deflector 65 will be supported upon the pressure arms 52 and upon the forward spacer bushings 46 which are engaged by the pressure arms 48. By making the slots 67 of sufficient length, the deflector is capable of vertical movement in both directions upon the spacer bushings 61 and 62.

The tongue 68 which depends between the adjacent arms 43 of abutting bails extends 65 first obliquely to the deflector, and then ap-

proximately normal to a plane tangent to the lower surface of the deflector, as shown in Fig. 8. When the deflector is in its upper position, which will be the position shown in Fig. 3 and occupied when the rollers 45 are in contact with the platen, the oblique section of the tongue 68 will be above the spacer bushing 64 and its free end section will extend along one side of that bushing 64. When the handle arm 59 is operated to rock the rod 38, the cams 56 will force the pressure arms 48 and 52 apart so as to release the pressure of the rollers 45 upon the platen.

Thereupon the rollers 45 will move away from the platen, and the deflector 65 will descend until the oblique section of the tongue 68 rests upon the spacer bushing 64 and checks the downward movement of the deflector with the arms 48 and 52. The deflector 65 may have an extension plate 70 extending rearwardly from and hinged to its rear edge, as shown in Figs. 2 and 5.

In order to lock the handle arm 59 in its angular position where it causes a release of the pressure of the rollers 45 upon the platen, a latch lever 71 may be provided. This lever is pivoted to the arm 59 at 72, and one end thereof is provided with a finger piece 73 which extends behind a similar finger piece upon the free end of the handle arm 59. The other end of the lever 71 extends angularly thereto and terminates in a hook 74 which is adapted to latch over a pin 75 provided upon one of the plates 11, and hold the handle arm 59 in its rearward position. The lever 71 may have ears 76 which embrace the handle arm 59 and limit the relative movement of the lever 71 upon the arm 59, but permit sufficient movement to allow operation of the lever into and out of latching engagement with the pin 75, when the handle arm 59 has been rocked rearwardly in order to cause a release of the pressure of the rollers 45 upon the platen.

The normal positions of the parts for feeding the paper through printing position are shown in Figs. 1, 2 and 3. In such positions, the rollers 45 will be pressed against the platen. The paper, with interleaved carbon sheets, if manifolding, is inserted into the throat of the machine between the rear of the platen and the paper table or deflector 65. Upon giving the platen a partial turn, the paper should, and normally does, pass into the control of the feed rolls around the deflector and under the bail, which latter should be in its forward or paper release position.

To adjust the paper to be typed after insertion, if it does not run squarely, or to adjust the paper for corrections, the operator first forces the handle arm 59 rearwardly and may pull the lever 71 towards the finger piece of the arm 59, so as to latch the hook 74 of the lever 71 over the pin 75 and hold the arm 59 in its rearmost position. When the arm 59 moves rearwardly, it will rock the rod 38 and

rotate the cams 56 in a direction to force the pressure arms 48 and 52 apart and thus release the pressure upon the roller spindle rods 44, whereupon the rollers 45 will move away from the platen so as to allow of the easy adjustment of the paper without obstruction.

As the arms 48 and 52 separate, the deflector 65 will descend until the tongue 68 rests upon the spacer bushing 64 of the rod 38, and this additional clearance between the deflector and the platen also facilitates the adjustment of the paper to be printed upon along the surface of the platen. When the paper has been adjusted to the desired extent, the operator releases the lever 71 from the pin 75, and the rod 38 is then rocked in a reverse direction to carry the cam noses 58 out of engagement with the arms 48 and 52. The springs 55 and bolts 53 thereupon force the arms 48 and 52 toward one another, yieldingly force the rollers 45 into contact with the platen, and elevate the paper deflector into normal position.

Before the upper edge of the paper passing between the deflector and platen has been carried upwardly through printing position by rotation of the platen, the holding bail formed by the arms 22 and cross bar 24 should be pulled forwardly past dead center position in order to facilitate the insertion of the upper edge of the paper under the cross bar 24. The bail carrying the rollers 25 may then be moved toward the platen so as to yieldingly press the upper edge of the paper, which has passed through printing position, against the platen, and thus hold it from falling forward or interfering with the action of the type bars.

The diameter of the screw 41 is preferably equal to or slightly greater than the diameter of the rod 38, so that in the assembly of the device, the rod 38 may be inserted endwise through the hole in the plate which normally receives the screw 41, and the screw 41 then inserted into that plate 11, with its shank 42 entering the recess 40 and rotatably supporting the rod 38.

It will be obvious that various changes in the details, which have been herein described and illustrated in order to explain the nature of the invention, may be made by those skilled in the art within the principle and scope of the invention as expressed in the appended claims.

I claim as my invention:—

1. Paper feeding mechanism for typewriters and the like comprising the combination with a platen, of a plurality of roller elements extending in directions along the length of the platen and spaced apart in a direction peripherally of the platen, supporting means for said elements permitting their movement toward and from the platen independently of one another and also per-

mitting an individual limited longitudinal tilting of each element, whereby each element may freely contact at points along its entire length with said platen, arms supported independently of the roller elements 70 extending in opposite directions peripherally of the platen, rockable independently of one another and bearing at their free ends upon said elements at points intermediate of their ends, and spring means for yieldingly urging 75 said arms in directions to press the roller elements against the platen, and permit tilting of the elements about the points of engagement thereof with the arms, whereby the pressure of said roller elements on the 80 platen will be uniform throughout their entire length.

2. Paper feeding mechanism for typewriters and the like comprising the combination with a platen, of a plurality of roller 85 elements extending in directions along the length of and spaced apart in a direction peripherally of the platen, a pair of separately pivoted arms supporting each element, each pair of arms permitting movement of its element toward and from the platen independently of the other element and a limited longitudinal tilting of that element, whereby each element may freely contact at points along its entire length with said platen, separately pivoted arms extending in opposite directions peripherally of the platen from approximately the same pivot, supported independently of the roller element, and bearing at their free ends upon said elements at 95 points intermediate of their ends, spring means for yieldingly urging said arms in directions to press the roller elements against the platen, and permit independent tilting of the elements about the points of engagement thereof with the arms, whereby the pressure of said roller elements on the platen will be uniform throughout their entire 100 length, and a cam device for forcing the arms away from the platen in order to release the paper for adjustment upon the platen.

3. Paper feeding mechanism for typewriters and the like comprising a platen, a support for the platen, a pivot rod extending parallel with the platen and carried by said support, separate arms independently pivoted on said rod and extending in opposite directions peripherally of said platen, said arms being arranged in pairs disposed upon the same side of the platen, an elongated roller element mounted in each pair of arms in a position parallel with the platen and oscillatable with the arms into and out of contact with the platen, a pair of contact arms 115 extending in opposite directions peripherally of the platen and bearing upon the roller elements at points approximately midway of the lengths of said elements, means for yieldingly urging said contact arms toward the 120 platen.

5 platen in order to yieldingly press the roller elements into contact with the platen, and a cam device interposed between the contact arms for forcing them apart in order to release the pressure of said roller elements against the platen.

4. Paper feeding mechanism for typewriters and the like comprising a platen, a support on which the platen is rotatably 10 mounted, feed roller elements disposed along the platen, positioned at spaced peripheral points thereof, arms carried by said support and mounting said elements for movement toward and from the platen, means for yieldingly pressing said elements against the platen, including a pair of arms connected to said support and pressing one upon each of said elements, and a cam device interposed between said pair of arms for forcing 15 them apart in order to release the pressure of the elements upon the platen.

5. Paper feeding mechanism for typewriters and the like comprising the combination with a platen and its support, of a rod carried by said support, extending in a direction parallel to the platen, and spaced somewhat therefrom, feed roller elements hinged to said rod for oscillation thereon into and out of contact with the platen, a pair of independently pivoted arms freely swingable toward and from the platen from opposite sides thereof and bearing upon said feed roller elements so as to force the latter against the platen, and a spring device connected between the arms for urging them toward one another and yieldingly forcing the feed roller elements into contact with the platen.

6. Paper feeding mechanism for typewriters and the like comprising the combination with a platen and its support, of a rod carried by said support, extending in a direction parallel to the platen, and spaced somewhat therefrom, feed roller elements hinged to said rod for oscillation thereon into and out of contact with the platen, a pair of arms freely swingable toward and from the platen from opposite sides thereof, and bearing upon said feed roller elements so as to force the latter against the platen, a spring 50 device connected between the arms for urging them toward one another and yieldingly forcing the feed roller elements into contact with the platen, and means for separating said arms to release the pressure on said elements.

7. Paper feeding mechanism for typewriters and the like comprising the combination with a platen and its support, of a rod carried by said support, extending in a direction parallel to the platen, and spaced somewhat therefrom, feed roller elements hinged to said rod for oscillation thereon into and out of contact with the platen, a pair of arms freely swingable toward and from the platen 55 from opposite sides thereof, and bearing

upon said feed roller elements so as to force the latter against the platen, a spring device connected between the arms for urging them toward one another and yieldingly forcing the feed roller elements into contact with the platen, and a cam disposed on said rod between said arms and operable to force them apart in order to release the pressure on said elements.

8. Paper feeding mechanism for typewriters and the like comprising the combination with a platen and its support, of a rod carried by said support, extending in a direction parallel to the platen, and spaced somewhat therefrom, feed roller elements hinged to said rod for oscillation thereon into and out of contact with the platen, a pair of arms freely swingable toward and from the opposite sides thereof and bearing upon said feed roller elements so as to force the latter against the platen, a spring device connected between the arms for urging them toward one another and yieldingly forcing the feed roller elements into contact with the platen, a cam disposed on said rod between said arms and operable to force them apart in order to release the pressure on said elements, said cam being fixed to said shaft, and said shaft being rotatably mounted in said support, and means for rocking said shaft to cam said arms apart.

9. Paper feeding mechanism for typewriters and the like comprising the combination with a platen and its support, of a rod carried by said support and extending parallel to the platen, bails hinged on said rod and extending in opposite directions peripherally of the platen so as to be movable into contact with the platen at spaced peripheral points thereof, rollers carried by said bails for contact with said platen and spaced apart at approximately the center of the length of the bail, a pair of arms supported for movement toward the platen and bearing upon said bails at such center points between the rollers, so as to press the rollers against the platen and permit longitudinal tilting of the bails, and spring means for yieldingly urging the arms toward one another so as to yieldingly press the rollers against the platen.

10. Paper feeding mechanism for typewriters and the like, comprising the combination with a platen and its support, of a rod carried by said support and extending parallel to the platen, bails hinged on said rod and extending in opposite directions peripherally of the platen so as to be movable into contact with the platen at spaced peripheral points thereof, rollers carried by said bail for contact with said platen and spaced apart at approximately the center of the length of the bail, a pair of arms supported for movement toward the platen and bearing upon said bails at such center points

between the rollers, so as to press the rollers against the platen and permit longitudinal tilting of the bails, a pin passing between the arms and permitting their relative movement toward and from one another, and a spring carried by said pin and forcing said arms towards one another, so as to yieldingly press the rollers into contact with the platen.

11. Paper feeding mechanism for typewriters and the like, comprising the combination with a platen, of a pair of paper feed elements mounted for movement into and out of contact with the platen, a pair of pivoted arms bearing upon said elements extending in opposite directions circumferentially of the platen and shiftable toward and from the platen so as to press the feed elements into contact with the platen, and a spring device connected between the arms for yieldingly urging them toward one another, so as to press the feed elements yieldingly against the platen.

12. Paper feeding mechanism for typewriters and the like, comprising the combination with a platen, of a pair of paper feed elements mounted for movement into and out of contact with the platen, a pair of arms bearing upon said elements and shiftable toward and from the platen so as to press the feed elements into contact with the platen, a spring device connected between the arms for yieldingly urging them toward one another, so as to press the feed elements yieldingly against the platen, a pin extending between the arms and permitting their relative movement toward and from one another, and a spring mounted upon said pin and yieldingly pressing said arms toward one another so as to press the elements into contact with the platen.

13. Paper feeding mechanism for typewriters and the like comprising the combination with a platen and its support, of a rod carried by said support, paper feed elements shiftable toward and from the platen at peripherally spaced points thereof, a yoke, a pair of arms pivoted in said yoke and extending in opposite directions peripherally of the platen and bearing upon said paper feed elements for forcing them toward the platen, and spring means connecting said arms for yieldingly urging them toward one another, so as to press the paper feed elements yieldingly into contact with the platen.

14. Paper feeding mechanism for typewriters and the like, comprising the combination with a platen and its support, of a rod carried by said support, paper feed elements shiftable toward and from the platen at peripherally spaced points thereof, a yoke, a pair of arms pivoted in said yoke and extending in opposite directions peripherally of the platen and bearing upon said paper feed elements for forcing them toward the platen,

spring means connecting said arms for yieldingly urging them toward one another, so as to press the paper feed elements yieldingly into contact with the platen, and a cam device mounted on said rod and operable, upon movement in one direction, to force said arms apart and release the pressure on said elements.

15. Paper feeding mechanism for typewriters and the like, comprising the combination with a platen, of a pair of paper feed elements mounted for movement into and out of contact with the platen, a pair of arms bearing upon said elements and shiftable toward and from the platen so as to press the feed elements into contact with the platen, a pin extending between the arms and permitting their relative movement toward and from one another, a spring mounted upon said pin and yieldingly pressing said arms toward one another so as to press the elements into contact with the platen, and means accessible from an end of the platen for forcing said arms apart to release the pressure of said elements upon said platen.

16. Paper feeding mechanism for typewriters and the like, comprising the combination with a platen and its support, of a rod carried by said support in spaced parallel relation to the platen, pressure feed elements hinged upon said rod, and extending in opposite directions peripherally along the platen from the rod, a U-shaped yoke, a pair of pressure arms hinged to said yoke and extending in opposite directions peripherally of the platen and bearing upon said elements so as to force the latter toward the platen, and a spring device connected between the pressure arms for urging them yieldingly in directions to force said elements against the platen.

17. Paper feeding mechanism for typewriters and the like, comprising the combination with a platen and its support, of a rod carried by said support and spaced in parallel relation to the platen, pressure feed elements hinged upon said rod, and extending in opposite directions peripherally along the platen from said rod, a U-shaped yoke, a pair of pressure arms hinged to said yoke and extending in opposite directions peripherally of the platen and bearing upon said elements so as to force the latter toward the platen, and a spring device connected between the pressure arms for urging them yieldingly in directions to force said elements against said platen, said pressure arms bearing upon said paper feed elements at points approximately midway of the length of the latter, the platen engaging portions of said elements being capable of longitudinal tilting to a limited extent relatively to the remainder of the elements, whereby the pressure upon said platen by said elements will be substantially uniform along the lengths of said elements.

18. Paper feeding mechanism for typewriters and the like comprising the combination with a platen, of a pair of paper feed elements shiftable into and out of contact with spaced peripheral portions of the platen, a pair of arms extending in opposite directions peripherally of said platen and bearing upon said elements for shifting the latter toward the platen, a pin extending from one arm slidably through the other and carrying an adjustable abutment, and a spring interposed between said abutment and the arm through which the pin slidably passes for urging said arms toward one another, whereby said elements will be yieldingly held in contact with said platen.

19. Paper feeding mechanism for typewriters and the like, comprising the combination with a platen, of a pair of paper feed elements, shiftable into and out of contact with spaced peripheral portions of the platen, a pair of arms extending in opposite directions peripherally of said platen and bearing upon said elements for shifting the latter toward the platen, a pin extending from one arm slidably through the other and carrying an adjustable abutment, a spring interposed between said abutment and the arm through which the pin slidably passes for urging said arms toward one another, whereby said elements will be yieldingly held in contact with said platen, and means including a cam element interposed between the arms for separating them in order to release the pressure of said elements upon the platen.

20. Paper feeding mechanism for typewriters and the like, comprising the combination with a platen and a support in which the platen is rotatably mounted adjacent its end, of a cam element extending parallel to and spaced from the platen, and rotatably mounted in said support, paper feed elements mounted for movement into and out of contact with peripherally spaced points of the platen, means for yieldingly urging said elements into contact with the platen, said cam element being effective upon said yielding means for rendering it ineffective when oscillated in one direction, and an operating handle connected to said cam element.

21. Paper feeding mechanism for typewriters and the like, comprising the combination with a platen, and a support for rotatably mounting said platen, of a bail element hinged by its arms to said support for movement into and out of contact with said platen, rollers adjustable along the cross arm of said bail for engagement with the platen, and a toggle link and spring element pivotally connected to an arm of the bail for yieldingly urging it in either direction from a dead center position in which it is out of contact with the platen, whereby said bail will be held yieldingly either in contact with the platen or urged in a direction away from the

platen, and means for limiting the movement of the bail away from the platen.

22. Paper feeding mechanism for typewriters and the like comprising the combination with a platen, and a support in which the platen is rotatably mounted adjacent its ends, of a bail hinged by its arms to said support, with the cross arm portion extending parallel with the platen and movable toward and from the platen upon oscillation of the bail, one of the arms of the bail extending beyond its pivot, a link pivoted to said extension of one of the arms of the bail and slidably and rockably mounted at its other end upon said support, and a spring interposed between said support and said link for urging said link in the direction permitted by its sliding movement, so as to urge said bail in either direction from a dead center position in which the sliding support, the pivotal connection between the link and the bail arm to which it is connected, and the pivotal support of said bail arm will be in a straight line, said bail when in dead center position being out of contact with the platen, whereby it will be urged yieldingly in either direction when displaced from said dead center position so as to be urged yieldingly toward or away from the platen.

23. Paper feeding mechanism for typewriters and the like comprising the combination with a platen, and a support in which the platen is rotatably mounted adjacent its ends, of a bail hinged by its arms to said support, with the cross arm portion extending parallel with the platen and movable toward and from the platen upon oscillation of the bail, a link pivoted to one of the arms of the bail and slidably and rockably mounted at its other end upon said support, and a spring interposed between said support and said link for urging said link in the direction permitted by its sliding movement, so as to urge said bail in either direction from a dead center position in which the sliding support, the pivotal connection between the link and the bail arm to which it is connected and the pivotal support of said bail arm will be in a straight line, said bail when in dead center position being out of contact with the platen, whereby it will be urged yieldingly in either direction when displaced from said dead center position toward or away from the platen, said bail and link having cooperating portions for limiting the movement of the bail in a direction away from the platen past dead center position.

24. Paper feeding mechanism for typewriters and the like comprising the combination with a platen, and a support in which the platen is rotatably mounted adjacent its ends, of a bail hinged by its arms to said support, with the cross arm portion extending parallel with the platen and mov-

able toward and from the platen upon oscillation of the bail, a link pivoted to one of the arms of the bail and slidably and rockably mounted at its other end upon said support, a spring interposed between said support and said link for urging said link in the direction permitted by its sliding movement, so as to urge said bail in either direction from a dead center position in which the 5 sliding support, the pivotal connection between the link and the bail arm to which it is connected and the pivotal support of said bail arm will be in a straight line, said bail when in dead center position being out of 10 contact with the platen, whereby it will be urged yieldingly in either direction when displaced from said dead center position so as to be urged yieldingly toward or away from the platen, said limiting means including cooperating abutments on the link and the tail of the bail.

25. Paper feeding mechanism for typewriters and the like comprising the combination with a platen and a support for the 25 platen, of a bail pivoted by its arms to the support for oscillation of its cross arm portion toward and from the platen, the pivotal points of connection between the support and one bail arm being at points intermediate the ends of said one arm, a link pivotally connected to the projecting end of said one arm and slidably and rockably mounted on said support, a spring device interposed between said link and said support for 30 yieldingly urging sliding movement of said link, the pivot of said one arm of the bail, the pivotal connection between the link and said one arm, and the rocking axis of the link upon the support being in a straight line when the cross arm portion of the bail 35 is spaced from the platen, whereby said bail will be yieldingly urged in either direction, toward or from the platen from the dead center position where the bail is out of contact with the platen.

40 26. Paper feeding mechanism for typewriters and the like, comprising the combination with a platen and a support for the platen, of a bail pivoted by its arms to the support for oscillation of its cross portion toward and from the platen, the pivotal points of connection between the support and one bail arm being at points intermediate the ends of said one arm, a link pivotally connected to the projecting end of said one arm and slidably and rockably mounted on said support, a spring device interposed between said link and said support for yieldingly urging sliding movement of said link, 45 the pivot of said one arm of the bail, the pivotal connection between the link and said one arm, and the rocking axis of the link upon the support being in a straight line when the cross portion of the bail is spaced 50 from the platen, whereby said bail will be

yieldingly urged in either direction, toward or from the platen from the dead center position where the bail is out of contact with the platen, said link and said one arm of the bail having inter-engaging abutment portions for limiting the movement of the bail in a direction away from the platen beyond 55 said dead center position.

27. Paper feeding mechanism for typewriters and the like, comprising the combination with a support, and a platen rotatably mounted in said support, of a paper holding bail having its arms hinged upon said support, one of said arms extending beyond its hinge, a link pivotally connected to the extension of said one of said arms to form an articulated continuation of said extension, a pin having sliding engagement with said link, and a spring acting between said pin and link, for resiliently urging said arm in either direction away from a dead center position of said device and arm, one of said directions being toward the platen, whereby said element will be yieldingly pressed against the platen when urged in said one of the directions and may be moved therefrom past dead center position.

28. Paper feeding mechanism for typewriters and the like, comprising the combination with a platen and a support therefor, of a bail pivoted by its arms to said support for oscillation to carry its cross portion toward and from the platen, a link pivoted to one of the arms of said bail and having a slot at its other end, a pin on said support receiving said slot, so as to slidably and rockably mount said link, a plate bearing against said pin and having apertures through which the arms of the slotted end slidably project, springs provided upon the arms of said slotted end and compressed between the plate and the unslotted end of the link, so as to urge the link endwise in a direction tending to remove it from the pin, and rock said bail in either direction from a dead center position in which the cross portion is out of contact with the platen, whereby the cross portion of the bail will be urged either into contact with the platen or in a direction away from the platen, depending upon which side 105 of the dead center position the springs are effective upon the bail.

29. Paper feeding mechanism for typewriters and the like, comprising the combination with a platen and a support therefor, of a bail pivoted by its arms to said support for oscillation to carry its cross portion toward and from the platen, a link pivoted to one of the arms of said bail and having a slot at its other end, a pin on said support receiving said slot, so as to slidably and rockably mount said link, a plate bearing against said pin and having apertures through which the arms of the slotted end slidably project, 110 springs provided upon the arms of said slot- 115

ted end and compressed between the plate and the unslotted end of the link, so as to urge the link endwise in a direction tending to remove it from the pin, and rock said bail in either direction from a dead center position in which the cross portion is out of contact with the platen, whereby the cross portion of the bail will be urged either into contact with the platen or in a direction away from the platen, depending upon which side of the dead center position the springs are effective upon the bail, said link and bail having interengaging abutment portions limiting movement of the bail in a direction to carry the cross portion away from the platen.

30. Paper feeding mechanism for typewriters and the like comprising a platen, a support for the platen, a pivot rod extending parallel with the platen and carried by said support, arms pivoted on said rod and extending in opposite directions peripherally of said platen, said arms being arranged in pairs, and the arms of each pair being disposed upon the same side of the platen, means connecting the arms of each pair and including spaced roller elements oscillatable with the arms into and out of contact with the platen, and a pressure arm bearing on each of said connecting means at points intermediate of the ends of said means, and between the roller elements thereon, said arms being biased in a direction to press the roller elements yieldingly against the platen.

31. Paper feeding mechanism for typewriters and the like comprising a platen, a support for the platen, a pivot rod extending parallel with the platen and carried by said support, arms pivoted on said rod and extending in opposite directions peripherally of said platen, said arms being arranged in pairs and the arms of each pair being disposed upon the same side of the platen, means connecting the arms of each pair and including spaced roller elements oscillatable with the arms into and out of contact with the platen, a pressure arm bearing on each of said connecting means at points intermediate of the ends of said means, and between the roller elements thereon, said arms being biased in a direction to press the roller elements yieldingly against the platen, and cam means effective on said arms for forcing them in directions to release the pressure of the roller elements upon the platen.

32. Paper feeding mechanism for typewriters and the like comprising the combination with a platen, of a pair of paper feed elements mounted for movement into and out of contact with the platen from opposite sides thereof, a pair of separate pivoted arms bearing one upon each of said elements and biased in a direction to press the feed elements into contact with the platen, and cam means effective upon said arms for releasing the pressure upon said elements.

33. Paper feeding mechanism for typewriters and the like comprising the combination with a platen, of a paper feed element mounted for movement into and out of contact with the platen and capable of a limited longitudinal tilting in order to contact uniformly for its entire length with the platen, and means bearing upon said element at approximately its central point and biased in a direction to press said element against the platen.

34. Paper feeding mechanism for typewriters and the like comprising the combination with a platen, of a paper feed element mounted for movement into and out of contact with the platen and capable of a limited longitudinal tilting in order to contact uniformly for its entire length with the platen, means bearing upon said element at approximately its central point and biased in a direction to press said element against the platen, and cam means effective upon the last named means for releasing the pressure of said element upon the platen.

35. Paper feeding mechanism for typewriters and the like, comprising the combination with a platen, of a paper holding bail element hinged by its arms for movement into and out of contact with said platen, a toggle link pivoted to said bail, and a spring mounted on said link and acting on it for urging it yieldingly in either direction from a dead center position in which said bail element is out of contact with the platen, whereby the bail will be held yieldingly either in contact with the platen or biased in a direction away from the platen, said link and the arm to which it is connected constituting toggle parts, one of said parts having a lug in the path of the other part for limiting movement of the bail in a direction away from the platen.

36. In a typewriting machine, a bearing rod, a roller rotatably and slidably mounted on said rod and having an internal annular channel, and a split sleeve confined within said channel and frictionally gripping said rod and freely rotatable relatively to said roller, whereby its frictional engagement with the rod will frictionally resist movement of the roller along the rod without restricting its rotation.

37. In a typewriting machine, a bearing rod, a roller rotatably and slidably mounted on said rod and having an internal annular channel at one end, and a portion of reduced diameter spaced endwise from the portion having the channel, a split sleeve confined within said channel and frictionally gripping said rod and freely rotatable relatively to said roller, whereby its frictional engagement with the rod will frictionally resist movement of the roller along the rod without restricting its rotation, and a sleeve of friction

material secured to the exterior of said reduced portion and rotatable therewith.

38. In a typewriting machine or the like, a bearing rod, a roller slideable and rotatable on said rod and having a hub at one end provided with an internal cavity, a friction device loosely confined in said cavity and frictionally engaging with said rod, whereby said roller will be freely rotatable on the shaft and frictionally held in various positions into which it may be adjusted by movement along the rod.

39. In a typewriting machine or the like, a bearing rod, a roller slideable and rotatable on said rod and having an internal cavity, a friction device loosely confined in said cavity and frictionally engaging with said rod, whereby said roller will be freely rotatable on the shaft and frictionally held in various positions into which it may be adjusted by movement along the rod.

40. In a typewriting machine or the like, a bearing rod, a sleeve rotatable and slideable on said rod and having an internal cavity opening into the bore, a friction device in said cavity having frictional engagement with said rod and loosely engaging said sleeve, whereby the frictional device will by friction resist adjustment of the sleeve along the rod without offering material resistance to the rotation of said sleeve, and a sleeve of friction material fitted upon and rotating with said first mentioned sleeve.

41. In a typewriting machine, a platen, a support for the platen, a pair of arms hinged on said support and extending into proximity to said platen, a rod loosely threaded at its ends into the free ends of said arms, rollers carried by said rod and engaging with the platen when swung thereagainst, and means for pressing said rod toward the platen, whereby said rod and rollers may tilt to a limited extent toward and from the platen in order to adjust the rollers into complete contact with the platen along their entire length, the threaded ends of said rod being formed to limit the extent to which the arms may be threaded thereon, whereby material rotation of the rod in either direction such as will tend to unscrew it from the arms will be resisted.

42. Paper feeding mechanism for typewriters and the like comprising a platen, a support for the platen, paper feed elements arranged in pairs along the platen, the elements of each pair being movable toward one another into contact with peripheral spaced points of the platen, means for yieldingly urging the elements of each pair toward one another and into contact with the platen including arms bearing upon said elements, a rod extending lengthwise of the platen and having cam portions interposed between said members for forcing them apart upon rotation of the rod in order to lessen the pressure of said elements upon the platen.

43. In a typewriter, a platen, a rod extending beneath the platen, bails hinged on said rod at points along the same, rollers carried by said bails and movable therewith into and out of contact with the platen, and a concave paper deflector disposed beneath the platen and between the platen and said rod, said deflector having tongues depending therefrom and having sliding engagement with said rod, whereby said rod will guide said deflector toward and from the platen, and also having a tongue extending between adjacent arms of said bails so as to be held thereby against movement endwise of the platen.

44. In a typewriter, a platen, a rod extending beneath the platen, bails hinged on said rod at points along the same, rollers carried by said bails and movable therewith into and out of contact with the platen, and a concave paper deflector disposed beneath the platen and between the platen and said rod, said deflector having tongues depending therefrom and having sliding engagement with said rod, whereby said rod will guide said deflector toward and from the platen, and also having a tongue extending between adjacent arms of said bails so as to be held thereby against movement endwise of the platen, said tongue which extends between the bail arms having an offset portion engageable with said rod to limit the movement of the deflector in a direction away from the platen.

45. In a typewriter, a platen, a rod extending beneath the platen, bails hinged on said rod at points along the same, rollers carried by said bails and movable therewith into and out of contact with the platen, a concave paper deflector disposed beneath the platen and between the platen and said rod, said deflector having tongues depending therefrom and having sliding engagement with said rod, whereby said rod will guide said deflector toward and from the platen, and also having a tongue extending between adjacent arms of said bails so as to be held thereby against movement endwise of the platen, means for biasing said bails toward the platen, said deflector being operable by said means and bails toward the platen to confine the paper deflector closely thereto when the bails are swung toward the platen and released to fall when said bails are removed from said platen.

46. In a typewriter, a platen, means extending parallel to and beneath said platen, a concave paper deflector disposed beneath said platen with its concave face toward the platen, said deflector being formed of sheet metal and having tongues extending therefrom and slidably engageable with said means, whereby the deflector will be guided toward and from the platen, paper feeding means associated with said platen and movable between effective and ineffective posi-

tions with respect thereto, and operable on said deflector to move it toward said platen when the paper feeding means is made effective and to release it for movement away from the platen when the paper feeding means is made ineffective.

47. In a typewriter, a platen, means extending parallel to and beneath said platen, a concave paper deflector disposed beneath said platen with its concave face toward the platen, said deflector being formed of sheet metal and having tongues extending therefrom and slidingly engageable with said means, whereby the deflector will be guided toward and from the platen, paper feeding means associated with said platen and movable between effective and ineffective positions with respect thereto, and operable on said deflector to move it toward said platen when the paper feeding means is made effective and to release it for movement away from the platen when the paper feeding means is made ineffective, said deflector also having a tongue engageable with said paper feeding means for preventing endwise movement of the deflector.

JOHN H. BARR.
